UNITED STATES PATENT OFFICE.

SAMUEL J. HOGGSON AND GEORGE C. PETTIS, OF NEW HAVEN, CONN.

METHOD OF COVERING KEY-BOARDS OF MUSICAL INSTRUMENTS.

SPECIFICATION forming part of Letters Patent No. 274,328, dated March 20, 1883.

Application filed November 27, 1882. (No model.)

To all whom it may concern:

Be it known that we, SAMUEL J. HOGGSON and GEORGE C. PETTIS, of New Haven, in the county of New Haven and State of Connecticut, have invented a new Improvement in Methods of Covering Key-Boards of Musical Instruments; and we do hereby declare the following, when taken in connection with accompanying drawings and the letters of reference marked thereon, to be a full, clear, and exact description of the same, and which said drawings constitute part of this specification, and represent, in—

Figure 1, the form with the blanks attached for seasoning purposes; Fig. 2, the key-board, showing the blanks as transferred thereto from the form; Fig. 3, an edge view of the form and key-board as placed together for the transfer of the blanks from the form to the board.

This invention relates to an improvement in the method of covering key-boards for pianos and like musical instruments with pyroxyloid, celluloid, or other plastic compound of which pyroxyline or soluble cellulose is a component part. In the use of this material for the coverings of keys in musical instruments it has been the usual plan to lay the material in a sheet upon the key-board, cement it thereto, and then cut out the keys. This must be done before the material has become thoroughly seasoned, or it will so twist and spring out of shape as to render it useless for covering. In seasoning it contracts to such an extent as to warp and twist the board out of shape, which makes it not only difficult to cut out the keys, but causes the loss of many keys, because of misshape, or because of air-bubbles, which unavoidably come between the board and sheet.

The object of our invention is to overcome this difficulty; and it consists in cutting the coverings from a sheet to the required shape, then securing them face downward and in reverse order upon a form, preferably of some fibrous or porous material, and there leaving them until thoroughly seasoned. Then, while the coverings are still secured to the form, cement the key-board to the coverings, and when the cement is hardened remove the form by applying any suitable solvent of the cement which secures the coverings to the form, then finishing the key-board in the usual manner, and as more fully hereinafter described.

We prefer as the material from which to make our coverings that which is described in Letters Patent granted to us August 23, 1881, No. 245,952, and which material is now known as "pyroxyloid." We take this material in a sheet of the required thickness and cut therefrom the coverings, say, for a set of keys, and before the material is thoroughly seasoned. These coverings we place face side down, and in reverse order, upon a form, A, as seen in Fig. 1, and secure them to the form by any cement which is easily soluble. The form we prefer to make from a fibrous material—such, for illustration, as a thick piece of hard felt; but it may be of any suitable material, as soft wood. We leave the coverings on the form until they are thoroughly seasoned. The seasoning may be performed by artificial or natural processes. When thoroughly seasoned we coat the surface of the key-board B evenly with a suitable cellulose cement and sponge or otherwise moisten the exposed surface of the coverings with alcohol and ether, and then place the cement side of the board upon the moistened surface of the covering, as seen in Fig. 3, and subject the whole to pressure to bring the wood and coverings firmly together, and there leave them until the cement is thoroughly dried. Then take from the press and moisten the form with a solvent which will dissolve the cement between the form and the covering, so that the form may be easily removed, leaving the coverings firmly secured to the key-board. The coverings being each independent of the other, the liability of air-bubbles is avoided, because the air can escape between the coverings, and the coverings being thoroughly seasoned before they are applied to the board, the trouble arising from the springing, warping, or twisting of the board or keys is avoided. The surface of the covering is finished and the key-board cut in the usual manner to separate the keys.

While we have described this invention as applied to the coverings made from our pyroxyloid, it will be evident that the same method may be employed in coverings made from celluloid or other plastic compound of which pyroxyline or soluble cellulose is a component part.

We claim—

The herein-described method of covering

keys of pianos and like musical instruments with pyroxyloid, celluloid, or like plastic material of which pyroxyline is a component part, consisting in cutting the coverings to shape, 5 cementing them upon a form face side down and in reverse order, to be there retained until thoroughly seasoned, and then, while the coverings are still held on the form, cementing the key-board to the exposed surface of the

covering, and when the cement is hardened removing the form from the face-surface of the coverings, substantially as described. 10
